Attorney

UNITED STATES PATENT OFFICE.

ERVIN J. RANTZ, OF FORT WAYNE, INDIANA.

CHIROPRACTIC TABLE.

Application filed March 23, 1921. Serial No. 454,634.

To all whom it may concern:

Be it known that I, ERVIN J. RANTZ, a citizen of the United States of America, and resident of Fort Wayne, in the county of 5 Allen and State of Indiana, have invented certain new and useful Improvements in Chiropractic Tables, of which the following is a specification.

This invention relates to improvements in 10 chiropractic tables, and the object thereof is to provide a table of its class having foot and head pedestals spaced apart with chest and abdominal supports intervening therebetween and arranged so that the pedestals 15 may be adjustably shifted to vary the space suitably for the accommodation of the stature of patients.

Another object is to afford an adjustable table of simple construction and operation. 20 And a further object is to provide an abdominal support so arranged in relation with the foot and head pedestals that it will automatically accommodate itself to the space between the pedestals.

25 The objects of the invention are accomplished by the construction illustrated in the accompanying drawing which is a side elevation of a table embodying the invention, parts being shown broken away and in section.

30 The characters of reference hereinafter appearing correspond with the similar characters on the drawing in the designation of the parts described.

35 The table is comprised of a supporting base 1 upon which are mounted a foot pedestal 2 and head pedestal 3, each of which is adapted to be adjustably shifted lengthwise upon the base and the space between 40 the pedestals thereby varied.

The front end of the foot pedestal 2 is open and a longitudinally movable spring bolster or abdominal support 4 mounted upon the base is adapted to telescope within 45 the pedestal 2. The abdominal support consists of a frame 5 that rests upon the base, and has a series of springs 6 mounted in the frame, there being a pliable case 7 extending over the tops of the springs and secured 50 to the frame and enclosing the springs. The abdominal support and head pedestal 3 are coupled together by means of a connecting

hook 8 so that as the head pedestal is moved the abdominal support moves therewith. The hook is of a suitable length so 55 that the space between the abdominal support and head pedestal is sufficient to accommodate the chest support 9 that is hinged to the rear upper part of the head pedestal and extends rearwardly therefrom. A torsional spring 10 is attached to the under side of the chest support and the rear end of the head pedestal and tends to hold the chest support in horizontal position.

The pedestal 2 has on the side thereof a 65 lock-bolt 11 adapted to engage a perforated plate 12 on the base and secure the pedestal in different positions. A hand hold 13, under the projecting top of the pedestal 3, is provided by which the operator may shift 70 the pedestal on the base, and a hand rest 14 is provided at each side of the base 1 for the convenience of the patient. The tops of the pedestals and chest support may be 75 provided with upholstery 15 such as is usually employed in apparatus of this kind.

In using the invention, the patient lies prostrate in the usual posture upon the table, the pedestals being spaced apart accordingly to suit the stature of the patient, and according to the degree of flexure intended to be administered to the portion of his body that rests upon the chest and abdominal supports. It will be understood that the greater the portion of the abdominal support that is exposed between the pedestals the degree of flexure that may be administered to the patient's body will be correspondingly greater, and that by merely shifting the head pedestal the abdominal 90 support will be exposed more or less accordingly.

What I claim is:

1. In a chiropractic table, a supporting base; a foot pedestal having an open front 95 end and adjustably supported on the base; a head pedestal movably supported upon the base, the pedestals being spaced apart; a hinged chest support extending rearwardly from the head pedestal and having tension 100 means in connection therewith for holding the same horizontally; and a resilient abdominal support movably mounted on the base between the pedestals and having tele-

scopic relation with the foot pedestal and connection with the head pedestal to be moved therewith.

2. In a chiropractic table, having foot and head pedestals adjustably spaced apart, a spring bolster having telescopic relation with one pedestal and connection with the other pedestal so as to be moved thereby

out of the one pedestal into the space between the pedestals as they are drawn apart. 10

In testimony whereof I affix my signature, in presence of two witnesses.

ERVIN J. RANTZ.

Witnesses:

MATILDA METTLER,
WALTER G. BURNS.
